UNITED STATES PATENT OFFICE.

JOHN F. NEWHALL, OF LYNN, MASSACHUSETTS, ASSIGNOR TO THE NEWHALL SHUTTER WORKING COMPANY, OF MAINE.

SHUTTER-WORKER.

SPECIFICATION forming part of Letters Patent No. 445,299, dated January 27, 1891.

Application filed July 18, 1890. Serial No. 359,220. (No model.)

To all whom it may concern:

Be it known that I, JOHN F. NEWHALL, of Lynn, in the county of Essex and State of Massachusetts, have invented new and useful Improvements in Shutter-Workers, of which the following is a specification.

This improvement relates to a device or apparatus whereby the shutters on the outside of a building can be opened and closed simultaneously from the inside, being especially adapted for use in buildings which are provided with metallic shutters intended to prevent the spread of fire, and it is an improvement on the United States Patent, numbered 429,793, granted to me June 10, 1890, to which reference is hereby made.

In the accompanying drawings, in which similar letters of reference indicate like parts, Figure 1 is an elevation representing shutters on the outside of a building provided with my improved device or apparatus. Fig. 2 is a horizontal section taken through the shutters. Fig. 3 is a vertical section taken on line *x*, Fig. 1. Fig. 4 is an enlarged cross-vertical section of one of the boxes *J* below described. Fig. 5 is a vertical section of the same, taken on line *y*, Fig. 4.

A *A* and *A'* *A'* represent, respectively, shutters on different stories of a building, of which *B* is a wall, and *B'* *B'* windows. *a a* are the hinges on which said shutters swing.

The lower edges of the shutters *A* and the upper edges of the shutters *A'* (on the next lower story) are provided with pins *C* *C'* or equivalent devices, to which is pivotally secured one end of the rods or links *D* *D'*, all substantially as in the said Letters Patent. The other ends of these connecting-rods are pivotally secured to posts *E* *E'*, whose oppo-

site ends *e e'* are enlarged and perforated to receive horizontal rods *H* *H'*, and are rendered adjustably rigid therewith by set-screws *f*. As will be seen, all the left shutters of two adjacent stories are connected with the rod *H* by means of the pins *C*, links *D*, posts *E*, and set-screws *f*, while all the right shutters are connected with the rod *H'* by means of the pins *C'*, links *D'*, posts *E'*, and set-screws *f*. The rods *H* *H'*, which are parallel and placed at the same height, are supported

by rollers *I* *I* and move between them and the upper rollers *I'* *I'*, all of said rollers having their bearings in the boxes or housings *J*, Figs. 4 and 5. These boxes are divided into two compartments by the central vertical partition *J'*, one compartment for each rod, and are closed at the tops, ends, and sides, excepting only that there are perforations in the ends large enough to admit the rods, thus protecting the rollers from rain or snow. The bottoms may be open. The boxes are supported by brackets *J''*, secured to the outside of the building-wall *B* between two stories.

K is a horizontal shaft extending through the wall *B* and having its bearings in the plates *L* and *L'*, secured to the outer and inner sides, respectively, of the wall. The inner end of this shaft has fixed to it a bevel-gear *g*, which is engaged by a bevel-gear *h*, fixed on the vertical shaft *N*, having its bearings in brackets *N'*, secured to the inner side of the wall *B*. An arm *O* extends up from one of these brackets *N'*, and a shaft *P* has its bearings in said arm and in a bracket *N''*, secured to the wall, said shaft engaging the shaft *N* by means of the bevel-gear *l m*, and being itself rotated by a crank *q*. On the squared outer end of this shaft *K* is centrally fixed a lever *R*, to whose opposite ends are pivotally secured the links or levers *S* *S'*. The outer ends of these levers *S* *S'* connect, respectively, with the rods *H* *H'*. It is evident, therefore, that by operating the crank *q* the shafts *P*, *N*, and *K* are rotated and the levers *R* *S* *S'* operated so as to move the rods *H* *H'* simultaneously in opposite directions, thus opening or closing all the shutters at once.

The shaft *N* and its connections are all inside the building, and hence not exposed to the weather, and it may extend to as many pairs of stories as desired. The levers *R* *S* *S'*, which are outside the building, are simple in construction and not likely to be affected by the weather.

The shutters may be locked in any position by means of a latch or hook *T*, supported by a bracket *T'*, said hook being adapted to be dropped into any one of the holes *t* in the hub *q'* of the lever *q*.

Having thus fully described my invention, what I claim, and desire to secure by Letters Patent, is—

1. The herein-described improved shutter-working apparatus, comprising the following parts, viz: the vertical shaft N, located within the building, supported by the wall thereof, and adapted to be operated by a crank, the horizontal shaft K, engaged by the shaft N by means of suitable gear and extending through to the outside of the building, the lever R, centrally engaged by the shaft K, the substantially parallel rods H H', supported on the outside of the building between two stories, the links or levers S S', having one end pivotally secured to the rods H H', respectively, and the other to the opposite ends of

the lever R, and the adjustable parts E E' and links D D' for directly operating the shutters, substantially as set forth. 20

2. In a shutter-working apparatus, the combination, with the actuating-rods H H', placed horizontally outside the building, of the boxes or housings J, containing the rollers I I', said housings being closed at their tops, sides, and 25 ends, with the exception of perforations of size to admit the rods, whereby the rollers are protected from rain or snow, substantially as described.

JOHN F. NEWHALL.
